UNITED STATES, PATENT OFFICE.

MICHAEL J. OWENS, OF TOLEDO, OHIO, ASSIGNOR TO THE TOLEDO GLASS COMPANY, OF
TOLEDO, OHIO, A CORPORATION OF OHIO.

CHARGING AND POKING MECHANISM FOR GAS-PRODUCERS.

1,273,177.

Specification of Letters Patent. Patented July 23, 1918.

Application filed November 5, 1914. Serial No. 870,375.

To all whom it may concern:

Be it known that I, MICHAEL J. OWENS, a citizen of the United States of America, residing at Toledo, in the county of Lucas and State of Ohio, have invented certain new and useful Improvements in Charging and Poking Mechanism for Gas-Producers, of which the following is a specification, reference being had therein to the accompanying drawings.

The invention relates to a charging and poking device for gas producers and consists in the construction of a device comprising a movable furnace top, one portion of which contains a series of pockets adapted to receive and discharge coal over the surface of the grates in the furnace and another portion adapted to be moved over the furnace and carrying a series of pokers; and further in the construction, arrangement and combination of the various parts as more fully hereinafter described and particularly pointed out in the claims.

In the drawings:

25 Figure 1 is a vertical central section through a furnace with my improved charging and poking device, showing also the coal bin with charging spouts, also in section;

30 Fig. 2 is a top plan view of the charging plate, partly broken away, part of the left-hand portion being taken from a point sectionally through the pokers and part in section through the guides for the lower end 35 of the poker, and Figs. 3 and 4 are enlarged sectional views of portions of Fig. 1.

A represents the furnace of a gas producer, the wall of which at its lower end is sealed in the tank B. Centrally in the furnace I have shown a revolving grate, C, resting on rollers, D, and driven by a screw, E, meshing with a worm, E'; these parts being of known construction and forming no part of my present invention. F represents the outlet for the gases from the producer, which, it will be seen, is below the top. G is the top, which I have shown made up of two cast plates, a, b, connected together by the flanges and bolts as shown 50 at c. The edges of these plates are provided with depending flanges, d, which project into a tank, H, extending at each side of the furnace a sufficient distance to take care of the travel of the top G and maintain a water-seal at all times. The parts a, b, respec-

tively, are each of sufficient size to completely cover the top of the furnace chamber, and each may be moved to covering position or to one side thereof. In order to effect this shifting, the top is provided with 60 suitable supporting wheels, I, running upon a track, J, beside the tank at the top. A suitable motor, K, I have shown upon the top, which, by any desired gearing, K', may drive a drive-pinion, L, meshing with a 65 rack M, beside the track, to propel the top forward and back to its two positions.

The section a of the plate G is provided with a series of coal pockets, O, registering with apertures O' through that section of the plate. These pockets O are provided at top and bottom with cut-off gates, h h', and any suitable operating devices may be employed for causing these gates to open and close. The upper series are arranged to be 75 in when the outer ones are out, and vice versa.

Arranged at one side of the furnace is a coal hopper, P, provided at its lower end with a series of discharge spouts, P', corresponding in number and location to the pockets O of the top G. The lower ends of these spouts are provided with corresponding cut-off gates i i'. When the top is moved beneath the hopper, each one of the 80 pockets O will register with a spout P'. Suitable crushed coal being placed in the hopper, if the gates i are open, the gates i' being closed, the coal will fill the chamber k beneath between the two gates in all 85 of the spouts. The gates i' are then closed and the gates h of the top are opened, while the gates h' are closed; then the gates i' are opened and the coal in the chambers k will be delivered into the chambers l of the 90 pockets in the top; the gates h are then closed and if the top be then moved from beneath the hopper to a position over the furnace (as shown in Fig. 1) and the gates h' opened, the coal will be delivered from 95 the pockets into the furnace and evenly distributed at all points thereon.

It is understood that the pockets O are arranged so as to make a substantially uniform distribution of the coal over all points 100 of the grate, as shown in Fig. 2.

When the top is moved to the right of the drawings, so that the pockets of the charging top are beneath the coal chutes, the section b of the top will be over the furnace. 110

This section, as will be seen by the drawings, carries the poking devices.

At four or more points on the section *b* of the top are secured posts, *Q*. At the top 5 of these posts is secured the head, *Q'*, in which is arranged one or more cylinders, *R*. In each cylinder is a piston, *R'*, connected to the piston rod *R''* which in turn is connected to a sliding head, *S*, guided upon the 10 posts *Q*. Suitable bumper springs *S'* are provided above and below the sliding head around the posts *Q*.

Connected to the lower end of the head *S* are a series of pokers, *T*, at their lower ends 15 projecting into tubular guides, *U*, formed on the upper surface of the part, *b*, of the top, and these may be provided with cups, *o*, for water packing.

When the pokers are arranged over the 20 furnace, by suitable air or water connections the sliding head *S* may be lowered and the ends of the pokers will project into and perforate the coal, substantially uniformly at all points as the pokers are distributed 25 over the entire bed of the furnace, as shown at the left-hand of Fig. 2. When out of use they may be withdrawn at their lower ends inside of a tubular guide, *U*, as shown at the left of Fig. 1.

The operation of the device having been 30 already explained, what I claim as my invention is:—

1. The combination of a gas producer furnace having an open top, a reciprocating cover-plate therefor, a series of pockets in 35 the plate, arranged to distribute coal uniformly over the grate surface, slides at the top and bottom of each pocket, and a complementary series of discharge chutes, arranged over the removed position of the 40 cover, substantially as described.

2. The combination of a gas producer furnace having an open top, a reciprocating cover-plate therefor, a series of coal pockets on one end of the plate, arranged to distribute coal uniformly over the grate area, a series of guide tubes on the other half of the plate, a series of reciprocating pokers in said guide tubes, means for reciprocating the pokers, said pokers being arranged to effect 50 the poking over the entire grate area.

In testimony whereof I affix my signature in presence of two witnesses.

MICHAEL J. OWENS.
